UNITED STATES PATENT OFFICE.

FREDERICK B. MACLAREN, OF JAMAICA, NEW YORK, ASSIGNOR TO THE MACLAREN ELECTRIC APPLIANCE CORPORATION, OF NEW YORK, N. Y., A CORPORATION OF DELAWARE.

REFRIGERATING MACHINE.

Application filed June 15, 1922. Serial No. 568,417.

This invention relates to improvements in refrigerating machinery and especially to that type in which air is used as a refrigerant.

- 5 One object of this invention is to provide a simple and comparatively inexpensive apparatus for the compressing and expanding of air; a further object is the provision of a rotary compressor without valve gear; 10 a still further object is the provision of a compound expander without valve gear. Other objects will appear from the following description of the invention at the end of which the invention will be claimed. 15 Another important object of the invention is to provide mechanism intermediate the compressing and expanding units which will transfer fluid from the compressor to the expander without a material diminution of pressure. Still another object is the provision of means for eliminating expansion volumetric capacity intermediate compressor and expander units, particularly as applied to refrigerating machinery. 20 The invention is illustrated somewhat diagrammatically in the accompanying drawings forming part hereof and in which Figure is a sectional elevation of the machine. 25 Fig. 2 is a detail showing the relative location of the shaft centers in the two compressor parts and it is a section taken on the line 2—2 of Figure 1 looking in the direction of the arrows, and 30 Fig. 3 is a section taken on the line 3—3 of Figure 1 looking in the direction of the arrows and it shows the location of the shafts of the low pressure part of the expander.

- 35 In the drawings 1 designates the motor frame and field yoke, 2 is the motor armature, 3 the commutator, 5 the field poles and 4 the field coils. The armature 2 is supported by the bearings 6 and 7 and drives 40 the gears 8, 9 and 10. Meshing with the gear 8 is a gear 11, which forms a compressor element. The gear 9 meshes with a gear 12 and forms the admission part of 45 the expander. The gear 10 meshes with the gear 13 and forms the expansion part of an air engine. The bearings 14, 15 and 16 support the main shaft while the bearings 17, 50 18 and 19 support the auxiliary shaft. A casing 20 is formed over the gears and is

made up of six cylinders in which the gears 55 revolve. Base plate 21 supports the motor, compressor and expander. The air inlet 22 delivers air to the gear-pump where it is compressed and forced out through the pipe 23 into the cooler or cooling coil 24. From 60 this cooler the air is delivered by pipe 25 to the inlet side of the admission element of the expander.

By reference to Fig. 3, it will be noticed that the gear 13 is located at an angle from the vertical in regard to gear 10. The exhaust from the admission element passes through the port 26 to the inlet side of the expansion element and the air after expansion is exhausted through the pipe 27 and 70 delivered to the point where refrigeration is required.

In action the motor drives the compressor element having the gears 8 and 11 taking air from the place to be cooled through the 75 pipe 22. This air is carried by the gear teeth around the casing 20 and delivered to the pipe 23. The gear teeth of the gears 8 and 11 should fit the casing 20 tightly except close to the point of meshing. The 80 compressed air passes through the cooler 24 where its temperature is dropped to a few degrees above that of the surrounding atmosphere and it is then led to the inlet side of the admission element of the expander 85 formed by the gears 9 and 12. This element acts as a cut-off for the air engine, a certain fixed amount of air being delivered at each revolution to the expander element formed by the gears 10 and 13. The 90 volume of the space left between the gear teeth and the casing in the expander element is much larger than in the admission element, therefore, the air expands doing work against the gear teeth and thus producing a drop in temperature. It is desirable that the length of the port 26 be quite short for efficient operation. I have found that the relative volumes of the three elements, compressor, admitter and expander 100 may well have substantially the ratio of 8—1—4 respectively.

The reason for eliminating as far as possible any length to the port 26 is to prevent expansion of the refrigerating fluid prior to 105 entry into the expander gear for if expansion occurred in the pipe length between the compressor and expander, no refrigeration

would occur. It is for this reason that the gears 13 and 10 are placed at an angle relative to the admission gears, this position permitting the shortest path between the admission unit and the expander and permitting entrance of the compressed fluid into the expander at the proper interval when the gears of the expander and admission element are separated. The compressed fluid is thus enabled to expand while doing work and consequently brings about a pronounced drop in temperature. The admission element carries a unitary charge of fluid under uniform pressure from the pipe line 25 into the expander and prevents a sudden drop of pressure which would occur if no mechanism in the nature of a valve were interposed between the compressor and expander.

It will be obvious to those skilled in the art to which the invention relates that modifications may be made in details of construction and arrangement without departing from the spirit of the invention and within the scope of the appended claims.

25 I claim:

1. A refrigerating machine comprising the combination of a gear-pump compressor, a gear-pump admission element operative as a cut-off for the compressor and having the centers of its gears in alignment with the centers of the gears of the compressor, a gear-pump expander having the center of one of its gears displaced in respect to the center of one of the gears of the admission element to accommodate a short port provided in the pump-casing from the admission element to the expander, a motor for the gear-pumps, a cooling coil connected to the outlet of the compressor and to the inlet of the admission element, and an air intake for the compressor and an air outlet for the expander, the volume of the compressor exceeding the volume of the admission element and the volume of the expander, and the volume of the expander exceeding the volume of the admission element.

2. In a refrigerating machine, the combination of a compressor unit adapted to compress refrigerating fluid, an expander unit, and an admission unit, each of said units being formed of interengaged gears, means intermediate the compressor and the admission unit for cooling said fluid, and a port intermediate the admission unit and expander unit, the volumetric capacity of the

port relative to that of the expander being small.

3. In refrigerating apparatus, the combination of a gear pump compressor adapted to compress a refrigerating fluid, a cooling means for said fluid connected to the compressor, a gear admission valve, a gear pump expander, a gear of said compressor and valve being positioned on a common shaft and another gear of said compressor and valve being positioned on a common shaft, and a gear expander adjacent the valve, one of the gears of said expander being mounted on a shaft in extension of one of said common shafts for the compressor and valve, and another of the gears of the expander being mounted with the shaft thereof displaced transversely from the plane of said common shafts, connections intermediate the compressor valve and expander, the length of the connection intermediate the expander in the valve being less than that of the connection between the compressor and valve, the volumetric ratio between the compressor, expander and valve being in decreasing magnitude, and means for operating said compressor.

4. In refrigerating apparatus, the combination of a power source, a gear pump compressor operatively connected to said power source comprising two adjacent shafts, a gear mounted on each shaft and meshing one within the other, and an enclosing casing, a gear pump admission valve adjacent the compressor having two gears mounted upon the extensions of the shafts of said compressor and an enclosing casing, a gear pump expander adjacent the valve and having two gears in mesh with each other, and an enclosing casing, one of said expander gears being mounted on an extension of one of the common shafts of the compressor and valve, and the other of said expander gears being positioned on a shaft displaced transversely from the plane of the adjacent shafts of the compressor and valve units, a cooling coil interposed between the compressor and valve; and a relatively short conduit intermediate the valve and expander, and a second conduit intermediate the expander and the compressor adapted to form a heat absorbing unit, said compressor, expander and valve having volumetric magnitudes in decreasing ratio.

FREDERICK B. MACLAREN.
